UNITED STATES PATENT OFFICE.

HANS LUTHI, OF KENOSHA, WISCONSIN.

SANITARY CLOSET-SEAT COVER.

1,071,953.

Specification of Letters Patent.

Patented Sept. 2, 1913.

Application filed March 28, 1913. Serial No. 757,319.

To all whom it may concern:

Be it known that I, HANS LUTHI, a citizen of the United States, and a resident of the city of Kenosha, county of Kenosha, and State of Wisconsin, have invented certain new and useful Improvements in Sanitary Closet-Seat Covers, of which the following is a specification.

My invention relates to sanitary covers for closet seats and the object of my improvement is to provide a perforated sanitary web and simple effective means for supporting and automatically passing said web across the seat of a closet by oscillating the latter on its hinges.

Other objects will appear hereinafter.

The invention consists in the combinations and arrangements of parts hereinafter described and claimed.

The invention will be best understood by reference to the accompanying drawings forming a part of this specification, and in which—

Figure 1 is a side elevation of a closet equipped with my invention, Fig. 2 is a plan view of a portion of the web used in the improvement, Fig. 3 is a section taken on line 3—3 of Fig. 1, and Fig. 4 is a section taken on line 4—4 of Fig. 3.

The preferred form of construction as illustrated in the drawings comprises a closet seat 5 carried by a closet bowl 6 in the usual manner and is of conventional construction. Secured to the forward edge of the seat 5 are arms 7 carrying a roller 8 upon which is wound a supply of webbing 9. The webbing 9 is provided with spaced perforations 10 and said perforations are adapted to register with the perforation in seat 5. The webbing 9 after being used is taken up by a take-up mechanism comprising a frame 11 supported on a bracket 12, in which is rotatably mounted shafts 13, 14 and 15. On the shaft 13 is loosely mounted a feed roller 16 and on the shaft 14 is rigidly secured a feed roller 17. The webbing 9 passes between the feed rollers 16 and 17 which are frictionally held together. The webbing passes around portions of feed rollers 16 and 17 substantially as indicated and is wound up on the roller 18 rigidly secured to shaft 15. The shafts 13 and 15 are mounted in slots 19 in a frame 11 and each of the bars 20 is hingedly connected to the frame 11 at one of its ends and a spring 21 connects the other end of two of said bars

20 to resiliently maintain rollers 16 and 17 in frictional engagement with roller 18. A hand wheel 22 is provided on shaft 15 to actuate the roller 18 when it is so desired.

Rigidly secured on shaft 14 is a spur gear 23 which is in mesh with a larger spur gear 24 rigidly secured on shaft 13 to cause shaft 14 to rotate with shaft 13. On the outer end of shaft 13 is rigidly secured a ratchet wheel 25 which is actuated by a pawl 26 carried on a lever 27 which is pivoted on shaft 13. The arm 27 is connected with the closet seat 5 by means of a connecting link 28 in a manner to cause rotation of feed rollers 17 and 16 upon oscillation of the closet seat 5 as will be readily understood. The size of roller 17 and the relative sizes of gears 23 and 24 and the throw movement of pawl 26 are so graduated as to cause the webbing 9 to be drawn across the closet seat 5 a distance equal to the distance between the centers of perforations 10 in webbing 9 so that when the webbing is placed over the seat 5 with one of its perforations 10 in registration with the perforation of seat 5 an oscillation of seat 5 from its full line position to its dotted line position and return as indicated in Fig. 1 will effect movement of the webbing 9 to cause its next perforation 10 to register with the perforation in seat 5. A spring 29 is carried on the under side of seat 5 in engagement with the roll of webbing 9 to prevent said webbing from unwinding too rapidly.

In use all that is necessary to move the webbing the required distance is to simply raise the lid 5 from its full line position to its dotted line position in Fig. 1 and return it again, to bring a new portion of the webbing in proper position on seat 5.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention which I claim as new and desire to secure by Letters Patent is:

1. In combination, a closet seat; a frame 110 mounted adjacent said closet seat and having slots therein; a shaft journaled through

- the central portion of said frame; a feed roller carried by said shaft; a second shaft rotatively mounted in slots in said frame; a second feed roller loosely mounted on said 5 second shaft; meshing gears on said first and second shafts; a ratchet and pawl gearing on said second shaft and operatively connected with said closet seat; a third shaft rotatively mounted in slots in said frame; a 10 web take-up roller on said third roller; and spring actuated levers engaging said second and third shafts binding said second feed roller and said take-up roller against said first feed roller, substantially as described.
- 15 2. In combination, a closet seat; a frame mounted adjacent said closet seat; two parallel shafts mounted in said frame; a feed roller rigidly secured on one of said shafts; a second feed roller loosely mounted on said 20 other shaft and adapted to coöperate with said first feed roller; meshing gears on said shafts; a ratchet-and-pawl gearing on one of said shafts; and a connecting link connect-
- ing said ratchet-and-pawl gearing with said closet seat, substantially as described. 25
3. In combination, a closet seat; a frame supported adjacent said closet seat; two parallel shafts mounted in said frame; a feed roller rigidly secured on one of said shafts; a second feed roller loosely mounted on said 30 other shaft, resiliently maintained against said first feed roller and adapted to coöperate therewith; meshing gears on said shafts; a ratchet-and-pawl gearing on one of said shafts; a connecting link connecting 35 said ratchet-and-pawl gearing with said closet seat; and a take-up roller in said frame and resiliently held against one of said feed rollers, substantially as described.

In testimony whereof I have signed my 40 name to this specification in the presence of two subscribing witnesses.

HANS LUTHI.
